C. W. WAILEY, OF NEW ORLEANS, LOUISIANA, ASSIGNOR TO NEW ORLEANS PNEUMATIC-PROPELLING COMPANY.

Letters Patent No. 84,030, dated November 19, 1868.

IMPROVEMENT IN PUMPS FOR COMPRESSING AIR

The Schedule referred to in these Letters Patent and making part of the same.

To all whom it may concern:

Be it known that I, C. W. WAILEY, of the city of New Orleans, parish of Orleans, and State of Louisiana, have invented a certain new and useful Improvement in Pumps for Compressing Atmospheric Air, with the view of using it as a motive-power; and I do hereby declare the following to be a full, clear, and exact description of the same, reference being had to the annexed drawing, making a part of this specification, on which is delineated a sectional view of my invention, the line of bisection being through the centre of the pump and its valves.

My invention consists of an improvement upon J. H. Johnson's pump for compressing atmospheric air, as patented by him in the Kingdom of Great Britain, April, 1860, said patent being numbered 890, by which the operation of said pump is made perfect in the attainment of the end for which it is desired.

But my invention will be better understood by referring to the drawing, on which A A' A" represent the main barrel of the pump, consisting of two vertical and one horizontal section, as shown, so as to be double, or capable of acting at each reciprocating stroke of the plunger or piston with the same power. From a to a', in the horizontal section, is the part in which the head B of the plunger works, and which must at all times be filled with cold water, in order to accomplish the designed object.

C C' are the valves through which the air enters the pump, and also a small stream of water, in order to keep up a surplus thereof in the barrels, and in this way secure a continual renewal of the said water, the carrying off of the caloric that has been absorbed by the water from the air, and the attainment of other important objects.

D D' are the valves through which the air is driven out of the pump, and into the reservoir or receiver in which it is to be compressed, by the water, as it is moved by the head B of the plunger. These valves open into and are connected by the pipe E, through which the air is impelled into the receptacle, in which it is compressed for use, by means of a proper conduit, connecting with it at F.

To put the pump in operation, the piston is placed at its full stroke, as shown at a, and the section A of the barrel of the pump is filled with cold water so completely as not to leave a particle of open space in it. This being done, the piston or plunger is moved, so as to bring the head B to the other extremity of its stroke at a'. In making this movement of the piston-head, the water will naturally follow the same, and hence a vacuum will be established in the vertical section A. This will open the valve C, and allow the air to rush in, and fill this section of the barrel.

As soon as the piston-head B has attained the point or extremity of its stroke, at a', the vertical section A' is in turn filled with water in the same way in which the section A was filled, to wit, through the induction-

valve C', as the section A was filled through the valve C. Both vertical sections being thus filled with water, as well as the horizontal section A", the pump is ready for action. That action is as follows: When the head B of the piston is moved back to a, the water in the barrel A is forced upward, and the air which had been admitted into said barrel or section of the pump being impelled in the same direction, the valve C having been closed by the spring d, passes out through the valve D, and as there is more water in this section of the barrel than there is space therein to contain it, every particle of air must necessarily be driven out, and, at the same time, such excess of water as may be in the said section, along with it, and up through the pipe E. At the opening F there is attached a spiral or coiled pipe, (not shown on the drawing,) which passes upwards, and through a tank of cold water, and into another tank, wherein the water is deposited, and from which it is drawn off by suitable discharge-cocks, the air, being the lightest, remaining on top, and hence removed from all danger of escape with the water as the same is drawn off. This arrangement secures the reduction of the temperature of the air beyond all per-adventure.

To prevent the water in the sections A A' of the barrel of the pump, as it is forced up in them by the reciprocating action of the plunger-head B, from impinging with too sudden and violent a shock against the heads G G', the inner surfaces of these heads are made concave, or arched, as shown. Thus formed, it will be seen that the water will meet with no abrupt resistance as it is driven up against the heads, and hence, that no severe shock can occur, while, at the same time, all the air must be driven out before the water reaches the ports of the induction-valves D D', by the concentric environment of it, by the up-rushing water, as it rises within the concavities of the heads.

The operation of the pump, whether the piston-head move in the one or the other direction, is precisely the same, and hence no further description is necessary.

The induction-valves C and C' are held up to their seats by the spiral springs d d', or they may be made to open and close at the proper times by a cam, or other equivalent mechanical device.

Having thus described my invention,

What I claim, and desire to secure by Letters Patent, is—

The combination of the concave heads G and G', with the vertical sections, A A', of a pump, through which flows a continuous stream of water, when the valves of the induction-ports are placed in said heads, and are operated by the springs d and d', substantially as set forth.

C. W. WAILEY.
